UNITED STATES PATENT OFFICE.

JOHN S. BLANKINSHIP, OF LYNCHBURG, VIRGINIA.

DESIGN FOR A PHONOGRAPH-CABINET.

55,363.

Specification for Design.

Patented June 1, 1920.

Application filed April 13, 1920. Serial No. 373,561. Term of patent 14 years.

To all whom it may concern:

Be it known that I, JOHN S. BLANKINSHIP, a citizen of the United States, residing at Lynchburg, in the county of Campbell and State of Virginia, have invented a new, original, and ornamental Design for Phonograph-Cabinets, of which the following is a specification, reference being had to the accompanying drawing, forming part thereof.

The figure is a front elevation of a phonograph cabinet, showing my new design.

I claim:

The ornamental design for a phonograph cabinet, as shown.

JOHN S. BLANKINSHIP.
